(57) **CLAIM**

The ornamental design for an insulated collapsible cup, as shown and described.

DESCRIPTION

FIG. 1 is a top perspective view of an insulated collapsible cup in accordance with the present invention;

FIG. 2 is a bottom perspective view thereof;

FIG. 3 is a top plan view thereof;

FIG. 4 is a bottom plan view thereof;

FIG. 5 is a front elevational view thereof;

FIG. 6 is a rear elevation view thereof;

FIG. 7 is a left side elevation view thereof; and,

FIG. 8 is a right side elevation view thereof.

The broken lines in the drawings depict portions of the insulated collapsible cup that form no part of the claimed design.

1 Claim, 5 Drawing Sheets
